Specification for Design.

Patented Mar. 13, 1917.

Application filed January 22, 1917. Serial No. 143,868. Term of patent 3½ years.

To all whom it may concern:

Be it known that I, CHARLES B. SPALSBURY, a citizen of the United States, residing at St. Louis, in the State of Missouri, have invented a new, original, and ornamental Design for Shoes, of which the following is a specification, reference being had to the accompanying drawing, forming a part thereof.

Figure I is a side elevation of the shoe showing my new design; and Fig. II is a front elevation thereof.

I claim:—

The ornamental design for a shoe substantially as shown.

In testimony that I claim the foregoing I hereunto affix my signature.

CHARLES B. SPALSBURY.
